PAPER-HOLDING ATTACHMENT FOR
DRAFTING BOARDS

Russell J. Wood, South Sudbury, Mass.

Application July 14, 1951, Serial No. 236,823

5 Claims. (Cl. 45—131)

1

This invention pertains to drafting tables or boards and more especially to a paper-holding attachment for such a table or board. When working upon large drawings, for example architectural drawings or large scale machine assemblies, it is often necessary for the draftsman to lean far over the board in order to reach upper areas of the paper. Such a position is not conducive to accuracy in his work; it is uncomfortable to the draftsman and over prolonged periods may result in physical disorders, and the rubbing of the draftsman's body over the lower part of the paper may result in blurring or smearing of the lines. I am aware of previous proposed attachments to drafting boards designed to permit shifting of the paper so as to bring any desired part of the sheet within easy reach, but all such devices known to me are complicated in construction, expensive to make and apply, and usually require major changes in the board or table with which they are to be assembled. I am also aware that it is a common practice among draftsmen to move the paper until its lower portion hangs down below the lower edge of the board, but this is undesirable, since it exposes the depending portion of the paper to damage by contact with the draftsman's body as he leans across the lower edge of the board.

One object of the present invention is to provide a very simple and inexpensive device for holding more or less of the drawing paper at the lower edge of the board and which may be applied to existing boards or tables by the use of simple attaching means which causes little, if any, damage to the board. A further object is to provide a paper-holding attachment for a drafting board or table so designed that the paper may be fed into it merely by applying downwardly directed pressure to the surface of the paper and without recourse to the use of rollers or other mechanical elements. A further object is to provide a paper holder readily attachable to the lower part of a drafting board or table and which does not in any way, either of itself or through its attachment, obstruct the upper surface of the board with respect to the free use of the customary drafting implements. A further object is to provide a paper holder of the class described which occupies but little space and which provides a smoothly rounded surface of substantial radius over which the draftsman may lean. A further object is to provide a paper holder for attachment to a drafting board or table comprising a single piece of sheet material curled to provide a concave guide surface with which the ad-

2

vancing edge of the paper may contact and which causes the paper to assume the form of a scroll devoid of sharp bends or creases. A further object is to provide a paper holder capable of retaining a substantial length of paper and from which the paper may readily be withdrawn at will. A further object is to provide a holder which may be swung upwardly to provide clearance for a drawer beneath the table. Other and further objects and advantages of the invention will be pointed out in the following more detailed description and by reference to the accompanying drawings wherein:

Fig. 1 is a fragmentary plan view showing the paper-holding device of the present invention mounted on the lower edge of a drafting board or table;

Fig. 2 is a fragmentary section, to larger scale, on the line 2—2 of Fig. 1;

Fig. 3 is a fragmentary vertical section, to larger scale, on the line 3—3 of Fig. 1;

Fig. 4 is a section, similar to Fig. 3 but on the line 4—4 of Fig. 1, showing the lower portion of a sheet of drafting paper coiled within the holder;

Fig. 5 is a fragmentary plan view illustrating a modification; and

Fig. 6 is a section on the line 6—6 of Fig. 5.

Referring to the drawings, the numeral 1 designates a drafting board or table such as customarily used by draftsmen for supporting the sheet of paper upon which a drawing is to be made. While this part 1 may be either a table, having its own supporting legs, or an independent drafting board, it is hereafter for convenience referred to as a drafting board. This board may be arranged horizontally, as here shown, but it is to be understood that it may be arranged on an incline as is also customary. This board has the top surface 2 and the edge 3, hereinafter referred to as the forward edge, this being the edge which is nearest to the draftsman while he is working. The board also has the left and right edges 5 and 6 respectively.

The paper holder of the present invention is here designated generally by the numeral 7 and is designed to extend along the lower edge of the drafting board and usually from the left-hand edge to the right-hand edge of the board, although it is not necessary that the length of the holder equal the width of the board. This holder 7 is conveniently made by bending a single sheet of stiff shape-retaining material, for example, sheet metal, to form a generally cylindiform volume comprising a single-convolution 8 which, as shown in Fig. 3, is so operatively located that

the lower edge surface of the board is tangent to the outer surface of the convolution 8. This convolution 8 forming the peripheral wall of a hollow casing which defines a paper-receiving chamber C having a cylindrically curved, concave inner surface 9, the axis of the convolution 8 being parallel to but spaced from the lower edge 3 of the board when the parts are assembled. As illustrated, the axis of the convolution 8 is above the plane of the lower surface of the board. The inner edge of the sheet forming the convolution 8 is indicated at 10. The outer marginal portion 11 of this convolution 8 is preferably substantially straight and tangent to the convolution proper and preferably has a finished edge 12, made for example, by folding the material upon itself, or otherwise providing a bead or rounded edge. The inner edge 10 of the convolution 8 is spaced from the inner surface of the straight tangent portion 11 so as to provide a space through which the paper may enter the chamber C within the holder. Except for its tangential portion 11, the entire volute is forward of the plane of the lower edge of the board, so that it may be applied to a board or table having a drawer or apron at its underside.

As illustrated in Figs. 2 and 3, the opposite end portions of the edge 12 are deflected downwardly, as shown at 13, to provide spacer elements for contact with the upper surface of the board, these spacer elements being provided with holes for the reception of fastener elements such as the screws 14 (Fig. 2) by means of which the holder may be secured to the board in the position of use. By the provision of the spacer members 13, the mediate portion of the edge 12 is raised from the upper surface 2 of the board so as to provide a vertically narrow entrance slot 15 (Figs. 2 and 4) through which the edge of the drafting paper P may be advanced inwardly into the chamber C.

In Figs. 5 and 6 a slight modification is illustrated wherein the same numerals indicate parts similar to those hereinbefore described. In this arrangement the marginal portion 11 of the outer convolution of the case is curled at its free edge 12^a (Fig. 5) about a reinforcing wire 16^a. The ends 16^a of this wire project at opposite ends of the case to form hinge pintles which are received in ears 17 formed in brackets 18 which are attached by screws to the forward edge of the drafting board 1. Preferably, although not necessarily, the brackets 18 are extended downwardly and forwardly to provide supports 19 for the opposite end portions of the casing 7. With this arrangement it is possible to swing the casing 7 upwardly about the axis defined by the pintles 16 and thus if the casing 7 be of such diameter as to project substantially below the lower surface of the board 1 it may be swung up out of the way to give access to a drawer or shelf beneath the board. With this arrangement the members 17 constitute the spacers for holding the part 11 spaced above the upper surface 2 of the board.

When herein the holder is referred to as "cylindrically" curved, this does not mean that the directrix of the curve is necessarily circular, since it may, and preferably is, some type of spiral.

In the use of this device and assuming that it has been attached to the drafting board and that drafting paper P rests on the upper surface of the board, if the draftsman finds it desirable to move the paper downwardly, that is, to slide it forwardly toward the edge 3 of the board, he may remove the fastening means which secures the paper to the board and merely by exerting

downwardly forwardly directed force upon the paper, that is, force directed toward the edge 3 of the board, the lower portion of the paper will slide through the slot 15 and, coming into contact with the concavely curved inner surface 9 of the holder, will gradually curl upon itself as shown in Fig. 4 to form a scroll, without necessitating the employment of a roller or other element for supporting the coiled paper. In the same way the paper may readily be withdrawn from the holder merely by exerting force in a direction away from the edge 3, the paper being freely drawn out from the chamber C, uncoiling as it is withdrawn.

Not only does this holder provide convenient means for coiling the paper and for protecting it from damage but it also provides a smoothly rounded abutment surface at the forward edge of the board, of a diameter which may be somewhat greater than the thickness of the board, as here illustrated, of a radius approximating the thickness of the board, and which thus provides a more comfortable surface against which the draftsman may lean than the usual square edge surface of the drafting board.

While as above suggested this holder may be made by curling a single sheet of stiff metal, it is contemplated as within the scope of the invention that it may be made in other ways and from other materials, for example, from one of the synthetic plastics or the like and that when made from such a material it may be made by a molding process or in any other suitable way. Moreover, although desirable ways of attaching this holder to the board have herein been suggested it is to be understood that any other suitable means for securing it in place may be employed within the scope of the present invention.

I claim:

1. A paper holder for use with a drafting board, said holder being of elongate tubular form comprising a single sheet of stiff sheet material curled to provide a paper holding chamber whose inner wall is cylindrically concave, the outer marginal portion of said sheet being substantially tangent to said concave wall and having a beaded edge, and hinge means for securing the holder to the drafting board, said hinge means being so designed that said marginal portion overhangs and is spaced from the upper surface of the board thereby to provide an entrance slot with the axis of the concave wall parallel to and above the forward edge of the board.

2. In combination with a drafting board having a flat upper surface, a lower surface, and a forward edge surface which is perpendicular to its upper surface, a paper holder comprising a part having a flat surface designed to contact the forward edge surface of the board, said part having openings therein for the reception of fasteners for attaching it to the board, a housing member hinged to said part to swing about a horizontal axis, said housing member having a concave, cylindrically curved, inner surface whose axis is parallel to the forward edge of the board, the upper portion of said curved surface being positioned to be engaged by the lower edge of a piece of paper resting upon the flat upper surface of the board as said paper is slid downwardly thereby to cause the paper to curl upon itself to form a coil adjacent to the lower edge of the board.

3. A paper holder for use with a drafting board, said holder comprising an elongate, hollow casing defining an interior paper-holding chamber

whose inner wall is cylindrically concave, said holder comprising a portion designed to overlie the forward part of the upper surface of the drafting board when the holder is assembled with the latter, and brackets hinged to the casing and comprising parts designed to receive fasteners for attaching them to the board whereby the casing may be swung upwardly from its normal position.

4. A paper holder for use with a drafting board, said holder comprising an elongate, hollow casing defining an interior paper-holding chamber whose inner wall is cylindrically concave, said casing comprising a portion designed to overlie the upper surface of the forward part of the drafting board when the holder is assembled with the latter, brackets hinged to the casing and comprising parts designed to receive fasteners for attaching the brackets to the forward portion of the board whereby the casing may be swung upwardly from its normal position, said brackets comprising parts which underlie and form supports for the opposite ends of the casing.

5. A paper holder for use with a drafting board having a flat upper surface, a lower surface and a flat forward edge surface which is substantially perpendicular to the upper surface of the board, said holder comprising a hollow

casing defining a substantially cylindrical chamber whose axis is parallel to the forward edge of the board and which is of a length to extend substantially from one side edge to the other side edge of the board, the holder having a vertically narrow, longitudinal paper-receiving slot at its top through which paper may be slipped into said chamber, the curved surface which defines the chamber terminating rearwardly at a longitudinally extending edge which is below the level of the upper surface of the board, the hollow casing which defines said cylindrical chamber being located forwardly of the forward edge of the board, and means for hingedly connecting the casing to the board whereby the casing may be swung upwardly from its normal position.
